UNITED STATES PATENT OFFICE

2,421,697

CARD TIME PRINTING AND PUNCHING RECORDER

Harold E. Hobby, Gardner, Mass., assignor to Simplex Time Recorder Co., Gardner, Mass., a corporation of Massachusetts

Application April 16, 1945, Serial No. 588,527

7 Claims. (Cl. 234—43)

1

This invention relates to a time recorder of the general type in which records are made on a separate card for each employee, which cards then show the time worked during each daily or other working period or the time worked on a certain job. Such recorders, producing a printed time record only, are in common use.

It is the general object of my invention to provide an improved card time recorder which will not only provide a printed record of the actual or clock time of starting and stopping work but will also provide a punched record adapted for use in a tabulating or calculating machine.

In the preferred form of my invention, these two types of records are made successively but as parts of a single registering procedure.

A further feature of the invention is the provision of means by which the set-up for the punched indication will remain unchanged during predetermined non-working periods, such as the noon lunch period or limited periods before "morning in" starting time and after "night out" stopping time.

My invention further relates to arrangements and combinations of parts which will be hereinafter described and more particularly pointed out in the appended claims.

A preferred form of the invention is shown in the drawings, in which

Fig. 1 is a left-hand elevation of my improved recorder, looking in the direction of the arrow 1 in Fig. 2;

Fig. 2 is a plan view, partially diagrammatic, of my improved recorder;

Fig. 3 is a partial sectional front elevation of the recorder;

Fig. 4 is a detail plan view of certain die plate supporting structure;

Fig. 5 is a partial plan view on an enlarged scale, looking in the direction of the arrow 5 in Fig. 3 and showing one set of punches;

Fig. 6 is an enlarged plan view showing three sets of selectors for the punches;

Fig. 7 is a bottom view showing a set of interponents for the punches;

Fig. 8 is a side elevation, partly diagrammatic, showing the control circuit and the timing disc which stops the feed of the punch selectors for predetermined periods;

Fig. 9 is a partial right-hand end elevation showing certain operating mechanism;

Fig. 10 is a detail view, looking in the direction of the arrow 10 in Fig. 9;

Fig. 11 is a right-hand side elevation showing the feeding mechanism for the selectors which

2

control the punches in the hundredths column;

Fig. 12 is a similar view of the feeding mechanism for the selectors for the tenths column;

Fig. 13 is a similar view showing the feeding mechanism for the selectors for the hour units and tens columns; and

Figs. 14, 15 and 16 are detail views showing the coaction of the different selectors with their respective interponents.

10 Briefly described, my improved time recorder comprises a base portion having feeding mechanism by which a record card is automatically advanced, stopped in punching position, thereafter again advanced and stopped in printing position, and finally delivered from the recorder to a suitable card-receiving device.

The punching mechanism comprises sets of punches preferably indicating time decimal in hours, tenths, and hundredths. A separate set 20 of such punches is provided for each of six registering periods, such as morning-in, noon-out, noon-in, night-out, extra-in and extra-out, and each of the punches in all of the sets has axial movement only in the base.

25 A further part of the recorder comprises a carriage movably mounted on the base and having time-controlled printing wheels and a stamping platen associated therewith and having also the punch-selecting mechanism shown in Fig. 6 and the interponents shown in Fig. 7. The carriage containing all of this printing and punch-selecting mechanism is shiftable on the base portion of the recorder transversely to the path of card travel, and is moved automatically transversely from each registering position to the next successive registering position by suitable program and shift mechanism.

I also provide a program control for the feed of the punch-selecting mechanism, which control can be so arranged that no selector feed takes place during certain predetermined periods. Commonly, the arrangement is such that the punch-selectors remain stationary during the entire noon lunch period and also during short periods before "morning-in" starting time and after "night-out" stopping time.

50 I also preferably arrange to stop the selector feed during the night or during some other non-working interval for an additional predetermined period of such length that the aggregate lost time will total just four hours. The aggregate of all operative periods during which the punches are progressively selected will then total twenty hours out of each twenty-four hour period.

55 The feed of the punch-selecting mechanism is

actuated by a separate synchronous motor mounted on the movable carriage, and this separate motor is controlled by any usual program disc on the carriage, which disc is continuously rotated in step with the type-wheel feeding mechanism.

Having described the general features of construction of my improved time recorder, I will now describe the various parts in detail.

In Fig. 2 I have shown a plan view of the base of the machine, with certain superposed parts indicated diagrammatically. The base comprises a frame having front and back frame members 20 in which a plurality of cross shafts 21 are rotatably mounted. Each of these cross shafts is provided with feed rolls 22 which underlie and support the record card and which feed it forward through the machine. Each cross shaft is provided at one end with a gear 23, which gears mesh with intervening idle gears 24 so that all of the cross shafts rotate in the same direction and at the same speed.

The gear 23 on the cross shaft 21 at the entering end of the recorder (or at the right in Fig. 2) is engaged by a gear 25 on a fixed stud 26 (Fig. 9). A second gear 29 is associated with the gear 25 and meshes with a large gear 31 mounted on a main cam shaft 32 rotatable in the frame members 20.

The shaft 32 is connected through any suitable one-revolution clutch 33 (Fig. 1) to a driving motor M which may rotate continuously during a registering period or which may be started up for irregular registrations. The clutch 33 may be engaged manually by the workman after placing his card in the machine, or the clutch may be electrically rendered operative by the act of placing the card in the machine, utilizing for this purpose any well-known card-controlled switch device, such as that shown for instance in the prior patent to Ruttiman and Deane, No. 2,330,-387, issued Sept. 28, 1943.

Upper tension rolls 34 are associated with the entering or right-hand feed rolls 22a (Fig. 9) and are of the same diameter as said feed rolls. Additional tension rolls 35 (Fig. 2) of smaller diameter are associated with other feed rolls 22. All of these tension rolls 34 and 35 are mounted on cross shafts 36 freely rotatable in bearings in bell-crank 37 (Fig. 3) and yieldingly pressed against the driving rolls 22 and 22a by tension springs 38.

Whenever the clutch 33 is engaged, all of the feed rolls 22 and 22a are positively rotated and all of the tension rolls 34 and 35 are rotated by frictional engagement with their associated feed rolls.

A gate 45 (Fig. 3) is provided for engagement by the record card C when it reaches punching position, and a second gate 46 is provided for engagement by the card when it reaches printing position. The gates 45 and 46 are mounted at opposite ends of a supporting lever 47 mounted on a fixed pivot 48 and by movement of which one gate is raised whenever the other gate is lowered.

The lever 47 (Fig. 3) is connected to a bent lever 50 freely pivoted on a cross shaft 51 and having a roll 52 (Fig. 9) engaging a cam 53 on the main cam shaft 32 previously described. As the cam shaft rotates, the cam 53 actuates the levers 50 and 47 to place the gates 46 and 46 alternately and oppositely in card-engaging and card-releasing positions.

A card feed plate 55 (Fig. 3) is mounted on arms 56 secured to a cross shaft 57 which is provided with an operating arm 58 having a cam roll

59 (Fig. 9). The roll 59 engages a relatively large cam 60 on the cam shaft 32. A spring 61 moves the feed plate 55 yieldingly to the left in Fig. 3 whenever a recess 62 in the cam 60 receives the cam roll 59. At such times, the feed plate 55 yieldingly advances the card C previously inserted by the workman, so that the leading edge of the card will be engaged by the feed rolls 22 and 21 and will be automatically advanced until it is stopped first by the gate 45, which at that time is held raised by the cam 53. The card is closely guided at its ends by the frame members 20 or guides associated therewith.

10 After the punching operation has been completed, the roll 52 passes off of the high portion of the cam 53, thus allowing the gate 45 to be lowered and the gate 46 to be raised. The feed rolls 22 will then advance the card to engage the second gate 46, in which position it will be held while the printing operation takes place. Thereafter the lever 50 will be again shifted by the cam 53 to reverse the gates and allow the card to be advanced by the feed rolls 22 to any suitable card-receiving device 64 (Fig. 3).

15 While in printing position, the card is forced upward against time-printing type-wheels W by a platen 65 which may be mounted at the upper end of a solenoid plunger 66 actuated by a solenoid coil 67. The solenoid circuit may be card-controlled as in Deane and Ruttiman cited and will be energized as the card is stopped in printing position. The use of the solenoid-operated platen is optional and in itself forms no part of the present invention.

20 The punches P (Figs. 3 and 5) which make the perforated record in the cards are mounted for vertical sliding movement in a punch plate 70 fixed in the base of the recorder. The preferred arrangement of one unit of punches for decimal time is shown in Fig. 5, with a row of punches P₁ for hundredths of an hour, P₂ for tenths, P₃ for hour units, and P₄ for hour tens. Each set of punches is thus adapted to register time by hundredths of an hour from zero to 19.98 hours.

25 In Fig. 2 I have indicated diagrammatically the relative locations of the punch units for six working periods. It will be understood that an entire separate set of punches as shown in Fig. 5 is provided for each registering period or position. Each of the punches for all of the registering periods thus occupies an individual position which is fixed relative to the positions of all other punches. In this way variations in punch position which might lead to inaccurate tabulating are avoided, as each punch always operates in the same fixed position.

30 Selector mechanism to be described is provided for holding down selected punches to give a correct time representation. The record card is forced up by a die plate 72 against the selected punches and thus receives perforations.

35 The die plate 72 (Fig. 3) is mounted on cross members 73 (Figs. 4 and 10) having depending portions 75 (Fig. 10) which are pivotally supported by the cross shaft 51 (Fig. 3) previously described. Slotted rolls 77 (Fig. 10) are mounted on the shaft 51 and constituting bearings therefor. These bearing rolls are mounted in and supported by arms 78 fixed on a cross shaft 79 (Fig. 3). An arm 80 on the cross shaft 79 has a cam roll 81 (Figs. 3 and 9) seated in a cam groove 82 in the side of a face cam 83. The arms 80 and 78 are thus oscillated to raise and lower the die plate 72, thus perforating the record

card. It will be noted that the shaft 51 which supports the gate lever 50 is also raised and lowered at the same time, so that the relative card-stopping position of the gate 45 remains substantially unchanged during the punching operation.

Spaced guide plates 85 and 86 (Fig. 3) constitute a vertically movable unit with the die plate 72. The guide plate 85 also serves as a stripper plate to move the card C downward and free it from the punches after perforation.

The card C is inserted in the narrow space 87 between the die plate 72 and the stripper guide plate 85. Two pairs of the feed rolls 22 project through slots in the end portions of the die plate 72 into said card space 87, and two pairs of upper rolls 88 are mounted in the vertically movable unit comprising the plates 72, 85 and 86. These rolls 88 coact with the feed rolls 22 in forwarding the card and in positioning it firmly against the stop gate 45.

It will be understood that the punches P are freely slideable vertically in the punch plate 70 (Fig. 3) and are frictionally slideable in the plates 85 and 86, and that they are each permanently aligned with an associated die opening in the die plate 72. The punches P, if not restrained from upward movement, will be lifted by the card as the card C and die plate 72 are lifted, and no corresponding holes will be punched in the card. If, however, any punch is prevented from rising, the plate 72 will push the card upward against and past the lower end of the punch P, and a corresponding hole will thus be made in the card. A punched record for tabulating purposes will thus be produced, which record will correspond to the time when the punching operation is performed.

The operation of the selectors and interponents which hold the selected punches in operative lower position and which prevent them from rising with the card and die plate will be hereinafter described.

Clock mechanism 90 is indicated diagrammatically in Fig. 3 and may be operated by a synchronous motor 91. Hour, minute and day type-wheels W are indicated in Fig. 3 and any other or additional type wheels or printing devices may be added.

Fig. 5 shows a set of punches designed to transform clock time in hours and minutes into decimal time in hours, tenths and hundredths. The transverse position of the punches corresponds to the numeral values 0 to 9 inclusive as indicated.

The punches P1 indicate the approximate decimal equivalents of periods of from one to six consecutive minutes the full six minutes constituting one-tenth of an hour. The period up to one minute is counted zero, the two minute period is counted as two one-hundredths of an hour, and the three, four, five and six minute periods receive the approximate decimal equivalents of four, five, six and eight one-hundredths respectively. The punches P2 indicate tenths of an hour from 0 to 9, the punches P3 indicate hour units from 0 to 9, and the punches P4 indicate 0 and 1 in the hour tens column. It is thus possible to indicate by perforations any time from 00.00 to 19.98 inclusive.

Selectors and interponents

In Figs. 14, 15 and 16 I have shown individual interponents and selectors for holding selected punches P in lowered or punching position.

In Fig. 15 I have shown a punch P1 held down

by an interponent 95 engaged by a lug 96 on a selector 97 mounted on a shaft 98 which is advanced at minute intervals to make five revolutions per hour and to thus bring one of the two lugs 96 of each selector 97 into operative position every six minutes.

The feeding mechanism for the shaft 98 is shown in Fig. 11 and comprises a synchronous motor M1 which operates a feed pawl 100 through a mutilated pinion 101, a segment gear 102, an arm 103, a link 104, and a second arm 105 on which the pawl 100 is mounted. The pawl 100 coacts with a twelve-tooth ratchet 106 on the shaft 98 and gives said shaft one revolution every twelve minutes, or a half revolution every six minutes. Overfeed is prevented by a stop 107 and reverse movement is prevented by a holding pawl 108.

The motor M1 runs continuously at the rate of one revolution per minute, except when rendered inoperative by a program-controlled cut-out to be described. Six two-lug selectors 97 are provided on the shaft 98 as shown in Figs. 6 and 15 and these selectors overlie six interponents 95, each of which is associated with a separate punch P1. The shaft 98 is advanced one space at the end of each six-minute interval, and each such advance movement brings the next lug 96 (Fig. 15) into position to hold its associated interponent 95 from rising. The associated punch P' is thus held in operative lower position in the punch plate 70.

In Fig. 14 I have shown a punch P2 held down by an interponent 110 engaged by one of the two lugs 111 on a selector 112, mounted on a shaft 114. The shaft 114 (Fig. 12) is provided with a twenty-tooth ratchet 115 which is intermittently advanced one space every six minutes or one-tenth of an hour by a feed pawl 116. The feed pawl 116 is mounted on a feed lever 117 actuated by a double cam 118 on the end of the shaft 98 previously described. The shaft 98, as previously stated, makes one revolution every twelve minutes and the double cam 118 thus operates the feed pawl 116 every six minutes or each tenth of an hour. The shaft 114 is thus given a complete revolution once every two hours. Overfeed is prevented by a stop 119 and backward movement is prevented by a holding pawl 120.

Ten selectors 112 (Figs. 6 and 14) are mounted on the shaft 114, and spacing plates or collars 122 are interposed between certain selectors. Ten interponents 110 are provided as shown in Figs. 7 and 14, and each interponent is associated with one of the punches P2 which show tenths of an hour. Where these punches P2 are aligned with punches P1 (Fig. 5), the corresponding interponents are offset laterally at their ends as shown at 110a (Fig. 7) to clear an adjacent interponent 95.

In Fig. 16 I have shown one of the punches P3 for hour units being held in lowered or punching position by an interponent 125 engaged by one of the two lugs 126 on a selector 127, which in turn is mounted on a shaft 128. The shaft 128 has a twenty-tooth ratchet 130 (Fig. 13) and is advanced one step each hour by a feed pawl 131 on a lever 132 pivoted at 133 and actuated by a double cam 134 on the shaft 114 previously described. The shaft 114 makes one revolution every two hours and consequently the double cam 134 operates the lever 132 and feed pawl 131 once each hour.

The ratchet 130 has twenty teeth, so that the shaft 128 is given a full revolution in twenty

hours. Program mechanism to be described holds the selector mechanism inoperative for four hours out of each twenty-four, so that the ratchet 130 and shaft 128 in effect make one revolution during each twenty-four hour period.

A stop 136 prevents overfeed and a holding pawl 137 prevents reverse movement, as in the feeding devices previously described.

Eight selectors 127 (Fig. 6) coat with eight interponents 125 (Fig. 7), and two additional selectors 127a (Fig. 6) coat with offset interponents 125a (Fig. 7), thus controlling the ten hour-unit punches P3.

Two additional selectors 140 (Fig. 6) coat with interponents 141 (Fig. 7) to control the two hour-tens punches P4 (Fig. 5). Each of these selectors 140 has a single lug extending approximately one-half of a circumference, so that the zero hour-tens punch P4 is held operative for the first ten hours, and the one punch P4 in the hour-tens column is held operative for the second ten hours of each twenty hour period.

Selector feed control

In Fig. 8 I have indicated diagrammatically the control of the selector feed, so that the feed will be operative twenty hours only during each twenty-four hour period. I have shown a four-lobe cam 145 mounted on a shaft 146 which is associated with the clock motor 91 in such manner that the cam 145 makes one revolution each hour. The cam thus operates the feed lever 147 once every fifteen minutes, and the lever 147 through a feed pawl 148, ratchet 149, pinion 150 and gear 151 advances a disc 152 to complete a full revolution each twenty-four hours, with a fractional advance movement every fifteen minutes.

A lever 153 engages the edge of the disc 152 and normally holds contacts 154 engaged. Cut-out portions 155 are provided in the edge of the disc 152 at any desired time intervals. When the end of the lever 153 drops into one of these cut out portions 155, the contacts 154 separate and the driving circuit of the selector motor M' (Figs. 8 and 11) is broken, thus holding the selector mechanism stationary until the lever 153 is raised and the contacts 154 are re-engaged. It will be noted, however, that the circuit for the clock-driving motor 91 is not broken, so that the control cam 145 which feeds the program disc 152 is continuously operated. Cut-outs 155 may vary in length from 15 minutes to 4 hours.

Type wheel drive

In Fig. 1 I have shown certain parts of the mechanism provided for intermittently advancing the type wheels W. The synchronous motor 91 previously described has an eccentric pin 160 which engages a feed lever 161 on each revolution and thereby causes a feed pawl 162 mounted on said lever to advance a 60-tooth ratchet 163 one space. The ratchet 163 is mounted on a shaft 164, which in turn supports a cam 165. The cam 165 engages a lug 166 on a feed lever 167 and thereby operates a feed pawl 168 to advance a 24-tooth ratchet 169 one space. The ratchet 169 may be mounted on the shaft 146 previously described. A stop 170 prevents overfeed and a holding pawl 171 prevents reverse movement.

The ratchet 163 makes one revolution in sixty minutes and the ratchet 169 makes one revolution in twenty-four hours. The minute type-wheel W is geared to rotate once an hour with

75 the ratchet 163, and the hour type-wheel is caused to rotate with the twenty-four hour ratchet 169. The program disc 152 previously described appears in Fig. 1 and is rotated by the mechanism shown in detail in Fig. 8. The cam shaft 146 also supports the twenty-four hour ratchet 169 as stated.

Carriage structure

10 I have already described the six punch units which are provided for the six usual daily registration periods. These punch units occupy fixed positions transversely of the machine. The record card is guided for straight-line movement 15 through the machine and with no transverse shift or displacement.

In order that the printed and punched records may occupy predetermined spaces lengthwise of the card, I mount the type-wheels and driving mechanism shown in Fig. 1, the program mechanism shown in Fig. 8, the punch selector mechanism shown in Fig. 6, the interponents shown in Fig. 7, and the platen with its solenoid-operating mechanism shown in Figs. 1 and 3 all on 20 a carriage R (Fig. 1) which is supported on fixed guide-rolls 180, two of which are shown in Fig. 1. It will be understood that such additional guide-rolls are provided as are necessary for firmly supporting and accurately guiding the carriage transversely of the base.

25 The transverse shift may be effected by gears 182 (Fig. 1) engaging rack bars 183 formed on the lower edges of the carriage R. These gears 182 are mounted on a shaft 185 (Fig. 2) driven 30 from a synchronous motor 186 through a periodic shift mechanism 187. This shift mechanism forms no part of my present invention and may be of the general type shown in the prior patent to Watkins and Dell, No. 2,101,205, issued December 7, 1937. Any usual ribbon and ribbon-feed mechanism may be provided for the type wheels W but this also constitutes no part of my invention and is omitted in Fig. 1 for the sake of clearness.

35 The solenoid coil 67 (Figs. 1 and 3) for the platen 65 is mounted in a depending frame structure 190 secured to the under side of the carriage R, so that it may move transversely with the type wheels and will remain at all times in vertical alignment therewith.

Summary

55 The construction of my improved recorder has been described in detail and it is believed that the general utility and operation has been made clearly apparent.

Briefly summarized, the carriage R shifts automatically at predetermined periods transversely of the path of card travel to bring the type wheels in alignment with the correct column on the card as designated in Fig. 2, and, so that for each working period the type wheels will coat with a selected punch unit to make a printed record of the actual time and a punched record of the decimal time in the right column whenever a card is presented and passed through the machine.

The decimal time, however, will be on a twenty-hour basis of actual working time and will automatically eliminate regular non-working periods, so that for computing purposes the punched records may be taken at face value. The usual provision is made for shifting the carriage rearward to receive irregular or extra "in" and "out"

records in the "extra" columns on the card shown in Fig. 2.

My improved recorder has the very important advantage of presenting a printed record of actual time for inspection by an employee and a punched record of decimal time which may be automatically tabulated and computed by machines provided for such purposes.

Having thus described my invention and the advantages thereof, I do not wish to be limited to the details herein disclosed, otherwise than as set forth in the claims, but what I claim is:

1. In a time recorder, in combination, card-punching mechanism, time printing devices, means to feed a card to said punching mechanism and to said printing devices, gates to stop said card in punching position and in printing position, and means to render said gates alternately and reversely operative.

2. In a time recorder having means to give a card a straight-line passage through said recorder, in combination, a plurality of card-punching units disposed in series transversely to the path of card travel, a carriage shiftable on said recorder and transversely to the path of card travel, and means on said carriage effective to render a different selected punch unit operative in each transverse position of said carriage.

3. In a time recorder having means to give a card a straight-line passage through said recorder, in combination, a plurality of card-punching units disposed in series transversely to the path of card travel, a carriage shiftable on said recorder and transversely to the path of card travel, rotatably mounted punch selectors on said carriage, time-controlled means to shift said selectors, and a separate interponent coacting with each selector to retain an associated punch in operative position.

4. In a time recorder, a series of punching units, a carriage shiftable along said series of units to coact with a selected unit only, a set of interponents in said carriage each associated with a particular punch in the selected unit, a plurality of selectors rotatably mounted in said carriage and each coacting with an associated interponent, time-controlled means to shift said carriage along said series of punch units, and

time-controlled means to shift said selectors in said carriage.

5. In a time recorder, a series of card-punching units each comprising a plurality of punches arranged to indicate decimal time, all of said punches being normally inoperative, time-controlled means to render selected punches in a selected unit operative at a predetermined time, and means to stop the feed of the time-controlled means for predetermined and selected non-working periods.

6. In a time recorder having time printing devices and means to actuate said devices continuously, in combination, card-punching devices, selectors for said punching devices, time-controlled means to advance said selectors, and devices to disable said time-controlled means for predetermined non-working periods during each twenty-four hours.

7. In a time recorder, a main cam shaft, means to give said shaft a single revolution, a cam on said shaft connected and effective to advance a card, feed rolls to receive said card, a second cam on said shaft connected and effective to stop said card in recording position, card-punching mechanism, a third cam on said shaft connected and effective to operate said punching mechanism to punch the card, after which operation said second cam releases said card.
